UNITED STATES PATENT OFFICE.

KATALIN GAÁL, OF GARFIELD, NEW JERSEY.

HAIR WAVER.

Application filed February 12, 1925. Serial No. 8,663.

To all whom it may concern:

Be it known that I, KATALIN GAÁL, a citizen of the United States, residing at Garfield, in the county of Bergen and State of New Jersey, have invented certain new and useful Improvements in Hair Wavers, of which the following is a specification.

This invention relates to devices for use in forming a hair wave. One object of the invention is to provide a hair waver which, while being simple and inexpensive, shall be so constructed as also to facilitate the operation of applying it to and removing it from the hair and to withstand the strain incident to its binding pressure on the hair though the mass of hair treated on any operation may be quite thick or heavy. To these ends both parts of the device, the frame member and the pivoted tongue member, are formed of flat metal strip material whose acting portions when operating to clamp the hair present the edges of the strip material thereto. In the preferred form of the invention the frame member is formed by bending a strip to form side arms and an intermediate arm and the tongue member is formed by bending a strip to form two arms, to alternate with the arms of the frame member, and pivoting portions. Other objects and advantages of the invention will appear hereinafter or be apparent to those skilled in the art.

In the drawings,

Fig. 1 is an underneath perspective view of the device, open, and Fig. 2 a top perspective view thereof, closed;

Fig. 3 is a side elevation, inverted;

Fig. 4 is a top plan; and

Fig. 5 a section on line 5—5, Fig. 4.

The frame member in the construction herein shown by way of example has a body portion *a* and two side arms *b* and also an intermediate arm *c* all projecting from portion *a* and spaced from each other, so that the frame member is bifurcated or forked. It is formed from a flat strip of stiff material, as metal, as follows: The strip is rebent at a point midway its length, thus producing the arm *c*; then its end portions are bent at right angles in opposite directions, and then these are bent again at right angles so that the extremities project in the same direction as and parallel with the arm *c*, thus producing the arms *b* and incidentally the body portion *a*. All the bends formed extend across the major width of the mate-

rial, so that each edge of the material remains in a plane for its full length.

The tongue member has a two-part body-portion *d*—*d*, a crotch *e* between the parts of said body-portion and an arm *f* projecting from each of said parts. This tongue member is formed from a flat strip of stiff material, as metal, as follows: The strip is rebent midway its length to form the crotch *e*. Each end portion thereof is then bent away from the other at approximately a right angle, then bent into parallelism with the other portion, then rebent outwardly with respect to the other portion, then bent away from the other portion at approximately a right angle, and then bent reversely to the last bend and approximately at a right angle, thus producing the arms *f*, the two-part body-portion *d*—*d* and also two projections *d*'—*d*'. All the bends formed extend across the major width of the material, so that each edge of the material remains in a plane for its full length.

The tongue member is assembled with the frame member so that the arm *c* of the latter is received by the crotch *e* of the former and the arms *b* of the latter extend outwardly of the projections *d*' of the former. The axis of pivotal movement of the tongue member on the frame member is afforded in the present instance by a pin *g* which penetrates the parts *b* *d*' *e* and *c*.

Preferably as viewed in side elevation the tongue member is arched, and in any case its arms *f* are of such length that when the tongue member is fully depressed their extremities will be received between the arms *b* and *c* of the frame member.

To hold the tongue member in the operative position there is a locking member. This consists of an elongated plate *h* having its end portions *h*' bent off in the same direction at right angles to form pivoting projections and having a lateral extension *h*² extending at right angles from the plate. This locking member is arranged with respect to the frame member so as to receive between its projections *h*' the end portion of the frame member having the body part *a*, so that said projections flank the arms *b* of the frame member; by rivets *i* the projections *h*' may be pivoted to said arms *b*. The plate *h* as viewed edgewise (Fig. 5) has a slight inward curvature so that when it is shifted on its pivot in either direction it wipes against the body portion *a* of the frame member and

requires to be sprung or distorted in order to complete the movement; thus the locking member is retained at either of its limits of movement.

5 In use the tongue member is introduced end-wise into the hair so as to leave a lock of the hair extending over it, whereupon the frame member is forced downward so as to receive the tongue member (Fig. 2) thus placing 10 the hair in a waved formation, and finally the locking member is shifted to the position of Figs. 2, 4, and 5 to hold the two parts in place. The device is easily removed by 15 swinging the locking member to the full-line position in Fig. 3 thus releasing the frame member, which may now be raised to release the waved lock of hair.

Having thus fully described my invention what I claim and desire to secure by Letters 20 Patent is:

1. A hair waver including a frame member formed of strip material bent to form three spaced rigidly related arms projecting in the same direction, and a tongue member formed 25 of strip material bent to form two spaced rigidly related arms projecting in the same direction, said tongue member being pivoted to the end portions of the arms of the frame member.

30 2. A hair waver including a frame member

formed of strip material bent to form three spaced rigidly related arms projecting in the same direction, and a tongue member formed of strip material bent to form two spaced rigidly related arms projecting in the same 35 direction and a crotch between the latter arms, said tongue member being pivoted to the end portions of the arms of the frame member and receiving in its crotch the end portion of the intermediate one of the later arms.

3. A hair waver including, with a frame member having a body portion at one end and spaced arms rigidly projecting therefrom in the same direction and a tongue member pivoted between and to the end portions of said arms on an axis connecting them, a locking member having spaced projections, pivoted to the body portion end of the frame member on an axis parallel with the first axis and movable on its pivot into and out of locking engagement with the free end portion of the tongue member when the latter is in clamping relation to the frame member, said locking member when pivotally moved being arranged to wipe at a point thereof between its said projections against and be thereby sprung by said end of the frame member.

In testimony wherof I affix my signature.

MRS. KATALIN GAÁL.
